A. P. VAN LOGHEM

CALENDAR

Filed Dec. 24, 1923

INVENTOR.

Arnold P. Van Loghem,
BY

Morsell Keeney & Morsell,
ATTORNEYS.

UNITED STATES PATENT OFFICE.

ARNOLD P. VAN LOGHEM, OF MILWAUKEE, WISCONSIN.

CALENDAR.

Application filed December 24, 1923. Serial No. 682,511.

To all whom it may concern:

Be it known that I, ARNOLD P. VAN LOGHEM, a citizen of the United States, and resident of Milwaukee, in the county of Milwaukee and State of Wisconsin, have invented new and useful Improvements in Calendars, of which the following is a description, reference being had to the accompanying drawings, which are a part of this specification.

This invention relates to improvements in calendars and more particularly to an approximately perpetual form of calendar.

It is one of the objects of the present invention to provide a calendar which will not have to be discarded at the expiration of a year, but can be used for an indefinite length of time.

A further object of the invention is to provide a calendar of the class described which can be arranged to indicate the day of the week of any particular date.

A further object of the invention is to provide a calendar of the class described which is very easily manipulated.

A further object of the invention is to provide a calendar of the class described which is of very simple construction, is strong and durable, is inexpensive to manufacture, and is well adapted for the purpose described.

With the above and other objects in view, the invention consists of the improved perpetual calendar, and its parts and combinations as set forth in the claims, and all equivalents thereof.

In the accompanying drawings in which the same reference characters indicate the same parts in all of the views:

Fig. 1 is a front view of the improved perpetual calendar;

Fig. 2 is view of the rear section of the calendar; and

Fig. 3 is a sectional view taken in line 3-3 of Fig. 1.

Referring now more particularly to the drawings, it will be seen that the numeral 5 indicates the improved perpetual calendar, the same being approximately circular in shape and consisting of a front section 6 and a rear section 7.

Near the top of the front section, an arc-shaped portion 8 is printed or otherwise delineated, said portion being divided into seven sections 9. Each of said sections contains the names of one or more months of

the year and all of the months appear. It should be noted, however, that the months "January" and "February" appear twice and in different sections and the second delineation of said months as at 10 and 11, differ from the first delineation. Any distinctive means of marking the second appearance of said months can be used and in the specific embodiment of the invention 60 red ink has been utilized. Above each of said sections 9, there is an aperture 12, the purpose of which will be hereinafter explained.

On the front section 6, there is also 70 printed the numerical designations of the days of a month. Said numerical designations are arranged in a manner similar to that of an ordinary calendar, as at 13, the numbers being in rows of seven beginning 75 at the left and continuing to the right and so on, through the number "31," thus forming five approximately horizontal rows and seven approximately vertical rows. Over each vertical row, there is an aperture 14, 80 the purpose of which will later be explained.

The rear section 7 is circular in form. Said section contains the names of the days of the week, the days being arranged in a circle in consecutive order. Twenty-one 85 days are so arranged, as at 15, making a total of three weeks. Arranged consecutively in circular form, as at 16, are a plurality of letters. As shown in the drawing, said letters range from "A" to "U" 90 inclusive. However, the number of letters so required depends on the number of small discs 17 utilized. Said discs are revolvably fastened to the section 7 near the periphery thereof and each disc is divided 95 into a plurality of quadrants 18, each quadrant having printed therein the number of a year. In the drawing twenty-one discs have been shown; therefore, but twenty-one of the letters shown at 16 are 100 required, one letter representing each disc. In a calendar constructed as shown in the drawing and provided with twenty-one discs, a total of one hundred and twenty-six years could be covered by the calendar, 105 inasmuch as each disc has printed thereon six different years. The calendar shown in the drawing, however, only includes one hundred years, ranging from 1900 to 2000, as some of the quadrants 18 have been left 110 blank.

Each of the sections 6 and 7 are provided

with central apertures 19 and 20 and the section 7 has a screw member 21 located within its aperture. A turn member 22 having a head member 22' threaded thereon passes through the aperture 19 and is connected to the bearing member 21, as shown in Fig. 3. In this manner, the front and rear sections are held together, being spaced apart by a filler 21'. The turn member 10 carries a pointer arm 23 and the parts are so arranged that a movement of the turn member will turn the pointer arm and also the rear section. The rear section is prevented from undesired movement by a 15 curved spring 24 adapted to lodge in circularly arranged depressions 25 formed in the section 6.

The operation of the calendar is as follows: The year desired may be selected from 20 tables 26 and 27 appearing on the front section, and adjacent the desired year a letter will appear. The rear section should then be rotated until the letter corresponding to the letter adjacent the selected year 25 appears in an aperture 28 formed on the front section. The appearance of said letter in the aperture indicates that the selected year will be found on the disc immediately above the aperture 28. The disc 30 should then be rotated until the selected year appears in the aperture 12. The pointer arm 23 is next loosened so that it may be independently brought into coincidence with the aperture 28, and is then again 35 tightened and moved to the desired month, and as was explained, the pointer and rear section are moved together. The resulting movement of the rear section will re-locate the arrangement of the days of the week 40 over the vertical rows at 13 and the result will be that the arrangement of numbers and days of the week at 13 will present a complete and true calendar for the year and month selected.

45 There is one exception to the aforementioned operation of the calendar and this exception occurs when the year selected is leap year and the month is January or February. The years on the various discs 50 which are leap years have a distinctive delineation from the other years, as at 29, and in the event of a leap year being selected the pointer should be turned to the "January" or "February" printed in red ink. The 55 rest of the operation is the same as was heretofore described.

It is obvious that the improved perpetual calendar can be so constructed as to include 60 an indefinite number of years. This is accomplished by filling in the blank quadrants on the discs with the desired years. Then

it is merely necessary to arrange the years in the tables and list after them the respective letter designations of their discs.

From the foregoing description it will be 65 seen that the improved perpetual calendar is of very simple and novel form, and is well adapted for the purpose described.

What I claim as my invention is:

1. A calendar, comprising a front section, 70 and a rear section revolubly connected to the front section, said front section having thereon a plurality of divisions having thereon the names of the various months, and the numerical designations of the days 75 of a month arranged in a calendrical manner, there being an aperture over each month division, and there also being seven apertures over the calendrical arrangement of the numerical designations of the days of a 80 month, and said rear section having thereon three sets of the names of the days of the week, and a plurality of discs revolubly attached to said section adjacent its periphery, each disc having thereon a plurality of 85 different predetermined year designations, the year designations and the names of the days being visible through the apertures in the front section, and means whereby a disc having thereon a selected year designation 90 may be located and arranged so that said year designation will register with the aperture adjacent the name of a selected month.

2. A calendar, comprising a front section, 95 and a rear section revolubly connected to the front section, said front section having thereon a plurality of divisions having thereon the names of the various months, and the numerical designations of the days 100 of a month arranged in a calendrical manner, there being an aperture over the month divisions, and there also being an aperture over the calendrical arrangement of the numerical designations of the days of a month, and said rear section having thereon 105 a plurality of sets of the names of the days of the week, and a plurality of movable members attached to the rear section adjacent its periphery, each movable member having thereon a plurality of different predetermined year designations, the year 110 designations and the names of the days being visible through the apertures in the front section, and means whereby a movable member having thereon a selected year 115 designation may be located and arranged so that said year designation will appear through the aperture over the name of the selected month.

In testimony whereof, I affix my signature. 120

ARNOLD P. VAN LOGHEM.
